UNITED STATES PATENT OFFICE.

ARTHUR N. OATHOUT, OF GLOVERSVILLE, NEW YORK, ASSIGNOR TO EDWIN L. MEYERS AND DAVID F. MEYER, CONSTITUTING THE FIRM OF LOUIS MEYERS & SON, OF NEW YORK, N. Y.

ATTACHMENT FOR SEWING-MACHINES.

1,072,489.

Specification of Letters Patent.

Patented Sept. 9, 1913.

Application filed April 18, 1911. Serial No. 621,889.

To all whom it may concern:

Be it known that I, ARTHUR N. OATHOUT, a citizen of the United States, and resident of Gloversville, Fulton county, New York, 5 have invented a certain new and useful Attachment for Sewing-Machines, of which the following is a specification.

My invention relates to an attachment for sewing machines, particularly adapted for 10 use in connection with machines such as are ordinarily used in making gloves, that is, making the seams and trimming stitches.

The invention has for its object to provide such machines with an attachment whereby 15 at the will of the operator the threads may be automatically knotted on the inside of the glove at any point during the operation and instantly restored to the properly adjusted sewing position, thereby avoiding the 20 disadvantages of the present process according to which all of the knotting of the threads is done by hand.

It will not be necessary to describe the sewing machine as a whole, except in so far 25 as certain elements thereof are necessarily described in order to show the co-operation of the parts of the machine with the action of my attachment since the machines as such are the usual sewing machines, the construction 30 of which is fully known. The fundamental principle upon which my attachment causes the sewing machine itself to knot the threads is a known principle and it will therefore be sufficient to define it by 35 stating that the sewing machine will knot the thread on the under surface of the fabric through which the needle passes if the fabric feeding devices are temporarily thrown out of operation so that the needle passes through 40 the same aperture two or three times in succession.

My invention provides an attachment which may readily be applied to any existing sewing machine, and which enables the 45 operator, without necessarily removing his hands from the work, to throw out of operation the fabric-feeding devices and also to cause such feeding devices to resume their normal operation at the exact adjustment as 50 to length of stitch etc. to which the machine had been previously set.

The invention is illustrated in the accom-

panying drawings, in which the preferred form of my invention is illustrated as applied to what is known as a Wheeler & 55 Wilson glove-stitching machine.

In the drawings Figure 1 is a horizontal section through the apron of the machine, taken along the line 1—1 of Fig. 2; Fig. 2 is an end elevation, taken from the right of Fig. 1; Fig. 3 is a partial transverse section taken along the line 3—3 of Fig. 1; Fig. 4 is a similar section, taken along the line 4—4 of Fig. 1; Fig. 5 is a similar section taken along the line 5—5 of Fig. 1; and Fig. 6 corresponds to the left hand side of Fig. 2 with the mechanism in released position.

A bed plate 1 is provided with a dependent marginal apron 2 and an end pedestal 3; the end portions of the apron together 70 with transverse ribs 4, 4' and the pedestals are provided with suitable bearings to receive the various operative shafts and spindles.

The machine is driven by a belt 5 which 75 engages a pulley fixed to shaft 6 and this shaft by means of an eccentric or crank (not shown) and links 7, 7 drives shaft 8 supported by the apron 2.

Pivots attached to rib 4' at 9 is a rocking lever 10 (Fig. 3) provided at one end with a yoke 11 embracing a cam 12 fixed to shaft 8, and at the other end with an integrally attached slideway 13 in which is adapted to slide a block 14 pivoted to one 85 end of a yoke adjusting link 15. The other end of link 15 is pivotally joined to an arm 16 rigidly attached to the feed dog operating shaft 17 supported just below the front of the bed plate. Near the other end of 90 shaft 17 (see Fig. 5) is a second arm 18 to which is pivotally joined one end of the feed link 19, said feed link carrying the feeder 20 and having its free end resting in a slide 21. This slide is pivoted at the end of a 95 short arm 22 fixed to a shaft 23. This shaft 23 carries a second arm 23' (Fig. 4) provided with a yoke 24 embracing a cam 25, fixed to one end of shaft 8, (as shown in Fig. 1.) A spring 26 (Fig. 5) keeps the 100 link 19 pressed against the slide 21.

Supported in the pedestal 3 (shown in dotted lines at the right of Fig. 1 and in section in Fig. 3) is a spindle 27, having

fixed thereto an arm 28 between the end of which and the link 15, and pivotally attached to both, is a link 29.

At the end of spindle 27, outside the 5 pedestal, is fixed a feed control lever 30 (see Fig. 2) having an eye in its outer end through which is passed a rod 31, having its upper part screw threaded. A pair of check nuts 32 are fixed to the rod above the 10 eye, and an adjustable nut 33 is similarly fixed below the eye. The rod 31 is long enough to pass through a suitable guide hole in the bed plate 1, and is connected below by a chain 34 to a foot treadle 35. A spring 15 36 kept under compression by the nut 39 is interposed between the bed plate 1 and the nut 39, and keeps the rod 31 and control lever 30 normally in the upper position as limited by the pin 40 projecting in the path 20 of the abutment 41 of the arm 30. Below the control lever and near its outer end is a stop screw 38, threaded in a support 37, which rises from the base plate.

From the above description it will be apparent that the feeding of the fabric is controlled by the amount of forward movement which is given to the feeder 20 (Fig. 5). The length of stitch is controlled initially by setting the shaft 27 (Fig. 3) to the desired position. This will cause the block 14 on the link 15 to change its position with reference to the axis of motion of the lever 10 and consequently effects to a greater or less degree the rocking of the shaft 17 which controls the forward and backward movement of the feeder 20. When, however, the block 14 is placed in a position corresponding with that of the axis of motion of the lever 10, then the shaft 17 will not rock at all and the feeder 20 will be moved neither forward nor back, and this, without affecting any other part of the sewing machine. The up and down movement of the feeder 20 is controlled by the shaft 23, the arm 22 and slide 21 (Fig. 5); the stitching mechanism, the needle and all the other mechanism of the machine will continue to operate and perform their functions precisely as at other times.

50 The operation of the machine provided with my attachment is as follows: The machine is first put into the ordinary operating condition and the length of the stitch determined by an adjustment of the stop 55 screw 38 and the apertured lever 30, so that when the treadle 35 is in the depressed condition shown in Fig. 2, a certain predetermined length of stitch will be taken by the machine. In this position the stop nuts 60 32 depressing the end of lever 30 cause the lever 30 to rest upon the head of the screw 38. In that position the machine carries out its normal operation of producing a series of equal stitches by feeding the fabric 65 intermittently beneath the needle and below

the presser foot, always for equal distances. The nut 33 is then so adjusted upon the screw threaded rod 31 that when the treadle 35 is released the spring 36 will force the nut 33 upwardly against the end of the lever 70 arm 30 until the abutment 41 engages pin 40 in which position the block 14 of Fig. 3 is located at the rocking axis of the lever 10, thereby preventing by a sudden and immediately operative change of location of these parts all rocking action of the shaft 17 and consequently all forward and backward movement of the feeder 20. In other words, when the treadle 35 of Fig. 2 is released, it instantaneously assumes the position shown in Fig. 6 and in that position the fabric will cease to feed through the machine but the needle will pass several times through the same hole and cause the thread to be knotted automatically on the 75 under side of the fabric. The operator may then at will, by merely depressing the treadle 35, either continue the same trimming stitch, or may take the fabric out of the machine and relocate it therein so that a new seam or trimming stitch may be begun at some other point. As soon as this re-adjustment of the fabric has been brought about, the treadle 35 is depressed and the machine begins to sew not only regular 80 stitches, but stitches exactly and precisely the identical length as those for which the machine had been originally adjusted.

It is obvious that instead of normally depressing the treadle 35 the attachment could 100 be so reconstructed that the operation is reversed and that the normal operation of the machine may be carried on during the un-depressed condition of the treadle and the feeder be thrown out of operation when the 105 treadle is depressed. Many modifications may also readily suggest themselves to anyone skilled in the art and are therefore within the scope of this invention.

I am aware that it is not new to throw the 110 feeder out of operation in a sewing machine, or to cause the thread to be knotted on the under side of the fabric and allow the needle to pass several times through the same aperture, but

115 What I do claim is:

An attachment for sewing machines comprising means for controlling the fabric feeding devices, a pivoted arm operatively connected therewith, lever mechanism adjustably secured to said arm, an abutment on said arm movable in the arc of a circle about the pivot of said arm, a fixed stop located in the path of said abutment and adapted to coöperate therewith to limit the movement of the arm in one direction, an adjustable stop located on said machine between said fixed stop and said lever mechanism and adjustable toward and away from said arm to limit the movement thereof 120 125 130

in the opposite direction, said lever mechanism being arranged to force said arm toward said adjustable stop, a compression spring adapted to normally maintain said abutment on the arm in engagement with said fixed stop and means for adjusting the tension of said spring.

In testimony whereof I have hereunto set my hand in the presence of two subscribing witnesses.

ARTHUR N. OATHOUT.
